A. H. MIDGLEY

ADJUSTMENT FOR THE MAGNETS IN TELEPHONE RECEIVERS AND THE LIKE

Filed August 25, 1925

Inventor
Albert Henry Midgley
By *Henry G. Midgley* Atty.

UNITED STATES PATENT OFFICE.

ALBERT HENRY MIDGLEY, OF UXBRIDGE, ENGLAND.

ADJUSTMENT FOR THE MAGNETS IN TELEPHONE RECEIVERS AND THE LIKE.

Application filed August 25, 1925. Serial No. 52,432.

To all whom it may concern:

Be it known that I, ALBERT HENRY MIDGLEY, a subject of the King of Great Britain, residing at Fairfield, Harefield Road, Uxbridge, in the county of Middlesex, England, have invented certain new and useful Improvements in and Connected with Adjustments for the Magnets in Telephone Receivers and the like, of which the following is a specification.

This invention comprises improvements in and connected with adjustments for the magnets of telephone receivers, loud speakers and the like and is concerned with arrangements in which the permanent magnet is supported by pivots about which it is adjusted by means such as a screw for giving an accurate adjustment of the pole tips in relation to the vibratory diaphragm or the like. In known arrangements the pole pieces have been carried at the free ends of limbs of a horse-shoe magnet supported pivotally at the opposite ends of the limbs. In such arrangements the flux between the pole tips 20 was parallel with the pivotal axis. When the faces of the pole tips are parallel with the diaphragm there is a magnetic flux which is uniform over the faces of the pole tips and the opposed portions of the diaphragm but when the magnet is pivotally adjusted so that the said faces are no longer parallel with the diaphragm but inclined thereto, a crowding of the lines of force takes place in those portions of the pole faces 30 which lie nearer to the diaphragm than others. In this way the incidence and the distribution of the magnetic flux is altered in performing the pivotal adjustment.

Now according to this invention, a pivotally supported telephone magnet structure has the pole pieces disposed in such a manner that the direction of the flux is at right angles to the pivotal axis and in the direction of the length of the magnet. With such an arrangement, the distribution of the flux remains about the same in spite of the fact that in the pivotal adjustment of the magnet, that pole piece which is farther from the pivot moves over a greater distance than 40 the pole piece which is nearer to the pivot.

In order to enable the invention to be readily understood, reference is made to the accompanying drawing illustrating one suitable construction in accordance with these improvements in which drawing:—

Figure 1 is a central vertical section of the base of a loud speaker containing a pivotally adjustable magnet structure in accordance with these improvements.

Figure 2 is a horizontal section on the line II—II of Figure 1.

Figure 3 is a perspective view of the framing formed by the bar magnets and yoke pieces, there being also seen in this figure the spring upon which one end of the magnet rests and the supports for such spring.

Referring to the drawing, *a* is the base of a loud speaker upon which is secured a vibratory diaphragm *b* in operative relation with magnet poles *c*, the diaphragm *b* being covered by a cap or cover *d* provided with a spigot *e* for the fitting on of a horn or trumpet (not shown) which may be of any suitable form.

The magnet structure comprises a pair of permanent bar magnets *m* which are braced apart by stout yoke pieces *n*, *n'* these bars and yokes being held strongly together by means of bolts and nuts at *o* and *o'*. The pole pieces *c* are secured against the inner ends of the yokes *n*, *n'* by wedging means *p* which are not further described herein as they form no part of this invention but are fully described and claimed in my patent application of even date. The magnet structure possesses strength and rigidity suiting it for the pivotal mounting now described. Also it will be seen that the yokes *n*, *n'* are spaced apart in the length direction of the magnet structure.

At one end of the structure, the bar magnets are fitted with centre point bearings. For example, the ends of the bolt at *o* may be formed with conical depressions or centres which are adapted for being engaged by centre point screws *q* screwed into the cast framing *r* secured within the base *a*, these screws *q* being adjusted so that their points engage pivotally with the centre point

bearing recesses aforesaid. The yoke piece n' is prolonged beyond the ends of the bar magnets m and such prolongation s may be of reduced thickness as shown. The prolongation s extends beneath a part of the casting r and rests upon a bow or blade spring t this spring being supported by adjustable nuts u screwing on screws v inserted from above through holes in the cover d and casting r . The spring t is slotted where it takes over the screws v as shown in Figure 3, in order that it may be free to flex under different degrees of adjustment pressure. An adjusting screw w provided with a milled head is screwed down through the casting r and so as to bear upon the top surface of the prolongation s of the yoke piece n' . By screwing down the screw w the magnet structure is depressed about its pivots q against the resistance of the spring t and the pole tips c are adjusted away from the diaphragm b or the like. Upon unscrewing the screw w the spring t or other resilient support elevates the magnet structure about the pivots q and the pole tips are adjusted towards the diaphragm b , as will be readily understood.

Referring to Figure 1, it will be seen that when the screw w is screwed down to depress the right hand end of the magnet structure, the gap between the tip of the right hand pole piece c and the diaphragm will be increased to a greater extent than the gap between the tip of the left hand pole piece c and the diaphragm. However, it will be apparent that such alteration of the gaps will simply increase the reluctance of the magnetic circuit without substantially altering the distribution of the lines of force flowing through the diaphragm.

The casting r may be a die casting in aluminum alloy or the like secured down upon the base a principally by means of screw and nuts x . The milled head of the adjusting screw w being situated at the top and at the periphery of the cover d it is very conveniently situated for instant operation and the adjustments can therefore be performed with much greater nicety and freedom than is possible when the head of the adjusting screw is situated beneath the base or at the back of a loud speaker. Furthermore, the terminals y, y' for the magnet coils may be on the top of the cover d so as to be readily accessible, as will be apparent from the drawing.

The hereinbefore described magnet structure is not the only suitable structure for the purpose of this invention, and the means for pivotally mounting and adjusting it can be varied without departing from these improvements.

I claim:—

1. Telephonic receiver comprising an elongated magnet structure, a pivot axis for

said structure at one end thereof; pole pieces secured in said structure at about the middle of its length and arranged one behind the other along a line perpendicular to the pivot axis, and adjusting means operative directly upon the free end of the structure to adjust the latter about said axis. 70

2. Telephonic receiver comprising an adjustable magnet structure composed of parallel bar magnets, yoke pieces spacing said bar magnets and pole pieces secured between said yoke pieces and against the inner ends thereof. 75

3. Telephone receiver comprising a magnet structure composed of parallel bar magnets and yoke pieces inserted as spacers between the end portions of said bar magnets, transverse securing bolts bolting together said bar magnets and yoke pieces, one of said bolts being adapted as an antifriction pivot bearing, and pole pieces secured against the inner ends of respective yoke pieces substantially as set forth. 80

4. Telephone magnet structure comprising a frame having permanent bar magnets for its longitudinal side members and yoke pieces spacing said bar magnets for its end members, polar formations on the inner ends of the yoke pieces, and pole pieces perpendicular to the plane of said frame and secured against respective polar formations. 90

5. Telephone receiver comprising a magnet structure composed of parallel bar magnets spaced apart by yoke pieces disposed between the end portions of said bar magnets, a pivotal support for one end of said structure, a resilient support for the opposite end of said structure, mechanical adjusting means operative in opposition to said resilient means, and pole pieces secured 100 in said structure against the inner ends of respective yoke pieces. 105

6. Telephone receiver comprising a magnet structure composed of parallel bar magnets spaced apart by yoke pieces disposed between end portions of said bar magnets, a pivot support for one end of said structure, an adjustable spring support for the opposite end of said structure, mechanical adjusting means operative upon said structure in opposition to said spring, and pole pieces secured in said structure in contact with respective yoke pieces substantially as set forth. 110

7. Telephone receiver comprising a magnet structure composed of parallel bar magnets spaced apart by yoke pieces disposed between end portions of said bar magnets, a pivot support for one end of said structure, a bow spring engaging beneath the opposite end of said structure, adjustable supports for the ends of said bow spring, an adjusting screw operable from above and acting downwardly on said structure against the resistance of said spring, and pole pieces 120

secured in said structure in contact with respective yoke pieces substantially as set forth.

8. In a telephone receiver a robust magnet structure comprising permanent bar magnets as longitudinal side members and yoke pieces inserted as spacers between end portions of said bar magnets; said bar magnets and yoke pieces being strongly bolted

together, pole pieces in longitudinal alignment and fixed in contact with respective yoke pieces, adjustable antifriction pivot devices supporting one end of said frame, and a mechanical adjustment operative upon the opposite end of said frame, substantially as set forth.

ALBERT HENRY MIDGLEY.
